ESTERS OF SUBSTITUTED SATURATED
FATTY ACIDS HAVING 12 TO 18 CARBON
ATOMSWolfgang Lübbert, Dusseldorf, and Erich Rosen-
hauer, Dusseldorf-Benrath, Germany, assign-
ors to firm Henkel & Cie. G. m. b. H., Dussel-
dorf, GermanyNo Drawing. Application November 29, 1932,
Serial No. 644,912. In Germany December 16,
1931

9 Claims. (Cl. 260—103)

The application Serial No. 644,911 discloses a process for the manufacture of esters of aliphatic or hydroaromatic hydroxy- or mercapto-compounds, the said esters being substituted in the acid radical.

The process consists in that hydroxy- or mercapto-fatty acids, which are arylated at the oxygen or sulphur, or their derivatives or substitution products, are esterified with such aliphatic or hydroaromatic compounds as contain at least one hydroxyl- or mercapto-group, and at least 6 carbon atoms.

It has now been found further that likewise valuable organic compounds are obtained when aliphatic compounds which contain at least one hydroxyl- or mercapto-group and less than 6 carbon atoms are esterified with such fatty acids, which are substituted by alkyl-oxy-, aryl-oxy-, aralkyl-oxy- or hydro-aryl-oxy-radicals, or the corresponding mercapto-compounds, as contain in the fatty acid radical 6 or more carbon atoms.

Instead of the aforesaid fatty acid derivatives, it is also possible to employ their substitution products. As such come into consideration, for example: radicals of the type specified, which are substituted by halogen, hydroxy-, sulphonic acid-, carboxyl-groups, hydrocarbon radicals, basic radicals and the like.

As fatty acid radicals, it is possible to employ the known fatty acids with normal or branched chain, provided they contain 6 or more carbon atoms, such as, for example, the stearic acids which are substituted in the α -position or in other positions by one or more alkyl-oxy-, aryl-oxy-, aralkyl-oxy- and hydro-aryl-oxy-radicals, or the mercapto-compounds corresponding to such stearic acids, furthermore α -methoxylauric acid or α -phenoxyauric acid or α -ethyl-thiostearic acid or the α -tolylthiobutyric acids and the like.

As aliphatic compounds containing hydroxyl-groups, it is possible to employ primary, secondary or tertiary alcohols or the corresponding mercaptans, provided they contain less than 6 carbon atoms. It is also possible to employ polyvalent alcohols or mercaptans of the said type.

The compounds containing the hydroxyl-groups or mercapto-groups may be of a saturated or unsaturated nature.

The said compounds, which contain the hydroxyl- or mercapto-groups may in their turn possess substituents of all kinds, such as carboxyl-groups or their derivatives, halogen atoms, ether groups, sulphonic acid-groups and the like.

The esterification of the components is effect-

ed in known manner with the free acids, if desired, in the presence of catalysts. It is also possible to employ derivatives of the fatty acids obtained by modifying the carboxy-group of the acids, such as chlorides, anhydrides, or the principle of alcoholysis may be employed, or the process may be carried out in such a manner that, instead of the hydroxy-compounds, their reactive derivatives, such as mineral acid esters or ester salts or alcoholates are employed.

Thus, for example, n-butyl α -phenoxyauric ester is obtained by the interaction of α -phenoxyauric acid chloride, obtainable from α -phenoxyauric acid and thionyl chloride, with n-butyl alcohol in carbon tetrachloride as solvent and diluent.

The new compounds possess to some extent emulsifying properties. They may be employed in the perfume industry, as softening agents and the like. Provided they possess groups which render them soluble in water, they have saponaceous properties. In addition, they serve as starting substances for further conversion products.

EXAMPLES

(1) Preparation of butyl α -phenoxyauric ester

27.9 parts of α -bromolauric acid are dissolved in about 100 parts of alcohol, and there are added thereto 9.4 parts of phenol and, gradually, 8 parts of NaOH, dissolved in about 60 parts of aqueous alcohol. The mixture is then heated to boiling on a water bath for five hours.

After evaporation of the alcohol and water in a vacuum, the sodium salt which is formed is re-crystallized from 96 per cent. alcohol, the halogen-free product is thereupon dissolved in water and is acidified with the calculated amount of hydrochloric acid. The free acid is extracted with ether.

After drying the ether extract with sodium sulphate and evaporation of the ether, the acid is treated with thionyl chloride. The acid chloride which is formed is added to an excess of n-butanol and the mixture is heated for 1 hour almost to boiling. Thereupon, the reaction product is diluted with water, is washed neutral with bicarbonate solution and the ether is evaporated after drying. The ester remains as a brownish colored oil. Purification by distillation in a high vacuum is not possible since phenol is split off.

(2) Preparation of ethyl α -phenylmercapto-stearic ester

27 parts of α -bromostearic acid are dissolved in about 150 parts of alcohol, 8.2 parts of thiophenol are added thereto and the whole is mixed with 6 parts of NaOH in about 100 parts of alcohol. After about 5 hours boiling on a water bath, the crystalline pulp, which separates out on cooling, is filtered off by suction. The said pulp consists of sodium bromide and the sodium salt of α -phenyl mercapto-stearic acid. This compound is converted into the free acid with excess of dilute hydrochloric acid, whereupon the said free acid is taken up with ether. After drying the ether extract with sodium sulphate and distilling off the ether, the acid chloride is prepared from the acid by means of thionyl chloride. To convert the acid chloride into the ethyl ester of α -phenylmercapto-stearic acid, the acid chloride is heated for about 1 hour with absolute alcohol on the water bath. The reaction product is diluted with water, the oil which separates out is taken up with ether, is washed neutral with sodium bicarbonate to remove hydrochloric acid, and after drying with sodium sulphate, the ether is distilled off. The ester remains as a yellowish oil.

We claim:—

30 1. The esters having the formula

in which R^2COO represents the acid radical of a saturated fatty acid having 12 to 18 carbon atoms, X represents O or S, R^1 represents a radical of a benzene hydrocarbon and R^3 an alkyl radical containing less than 6 carbon atoms.

2. The esters set forth in claim 1 wherein X is oxygen.

3. The esters set forth in claim 1 wherein X is sulphur.

4. The esters set forth in claim 1 wherein R^1 is a phenyl radical.

5. The esters set forth in claim 1 wherein R^1 is a tolyl radical.

6. The esters set forth in claim 1 wherein R^3 is an ethyl radical.

7. The esters set forth in claim 1 wherein R^3 is a butyl radical.

8. Butyl α -phenoxylauric ester which may be represented by the formula

9. Ethyl α -phenylmercaptostearic ester which may be represented by the formula
